American Seating Company, Grand Rapids, Mich., a
corporation of New Jersey

Application August 9, 1956, Serial No. 42,584

Term of patent 14 years

(Cl. D33—7)

The figure is a perspective view of a desk showing my new design, the back of the box element being enclosed and plain.

The dominant features of my design reside in the portions shown in full lines.

I claim:

The ornamental design for a desk or the like, substantially as shown and described.
